UNITED STATES PATENT OFFICE.

STANISLAW GRZYBOWSKI, OF FORT WAYNE, INDIANA.

SHIP'S TABLE.

1,142,163.

Specification of Letters Patent.

Patented June 8, 1915.

Application filed February 25, 1915. Serial No. 10,491.

To all whom it may concern:

Be it known that I, STANISLAW GRZYBOWSKI, a subject of the Czar of Russia, residing at Fort Wayne, in the county of Allen and State of Indiana, have invented certain new and useful Improvements in Ships' Tables, of which the following is a specification.

This invention relates to certain new and 10 useful improvements in ships' tables.

An object of the invention is to provide a table for ships that will always assume a horizontal position so that the articles resting thereon will not be upset or thrown 15 therefrom when the ship carrying the same encounters rough seas.

A further object of the invention is to provide a ship's table of the self-leveling type and wherein the weight is laterally adjustable relative to the table base so that the 20 same may be set to assume a normal horizontal position regardless of any defects in the construction or manufacture of the table.

25 With the above general objects in view and others that will appear as the nature of the invention is better understood, the same consists in the novel construction, combination and arrangement of parts to be herein- 30 after more fully described and then claimed.

In the accompanying drawing in which is shown the preferred embodiment of the present invention and to which reference is had herein by like characters designating 35 corresponding parts throughout the several views:—Figure 1 is a vertical sectional view of a ship's table built in accordance with the present invention. Fig. 2 is a detail sectional view of a portion of the table supporting base member with the weight attached thereto and the suspending bolt for the weight partially broken away, better to illustrate the slotted base. Fig. 3 is a bottom plan view of a portion of the top supporting base, illustrating the communicating angularly-disposed dove-tailed slots, and, 45 Fig. 4 is a detail view, partly in section, of one of the supporting legs, illustrating the manner of retaining the ball bearings in 50 position.

Referring more in detail to the accompanying drawing, the reference numeral 10 designates the table top which may be of any suitable shape in plan view, either square, 55 round, or as desired, and the supporting member therefor includes the bowl-shaped mem-

ber 11 increased in cross-sectional area at the lower end thereof, and which portion is designated 12, while the upper free edge thereof carries an outwardly-directed annular flange 13, through which the fastening means 14 extends for securing the same to the table top 10.

The supporting members for the base member 11 includes the legs 15 which are 60 connected by the band 16 for holding the same rigid while the upper ends thereof are provided with removable heads 17 adapted for supporting the base 11. The removable heads 17 carry screws 18 adapted to be received in the upper ends of the legs 15, and as shown in Fig. 1, are preferably formed triangular in side elevation. The upper wall of the head 17 is provided with a central opening 19 through which the anti friction ball 20 projects as shown in Fig. 1. A lateral recess 21 is formed in one of the side faces of the head 17 to facilitate the positioning of the ball 20 within the head and this recess is closed by the side plate 22 70 held in position by the fastening screws 23. Any suitable number of legs 15 may be provided, and of course the balls 20 projecting through the openings 19 in the heads 17 afford a rolling contact for the table base 80 supporting member 11.

The outer bottom face of the member 11 is constructed to constitute a support for a pendant weight, and as shown in Figs. 2 and 3, the lower end 12 of increased cross-sectional area is provided with angularly-disposed dove-tailed slots 24 provided at their outer ends with enlarged openings 25 while the inner ends thereof meet to provide a common central opening 26. The pendant 90 weight 27 is mounted on the bolt 28 while the head 29 of the bolt is positioned within the dove-tailed slots 24 as shown in Fig. 1, and to hold the weight in position on the bolt 28, I have provided the lock nut 30 95 threaded on to the lower end of the bolt.

The head 29 of the bolt is introduced into the slots 24 through either of the enlarged end openings 25 and the bolt may then be shifted to the desired position through the 100 slots and pass the common central opening 26 to enter the desired slot. Should the table be constructed so that when the weight 27 is centrally disposed, it will assume an angular position, the said weight and carrying bolt 28 may be shifted in the desired direction through the preferred slot 24 and 110

be held in such position by tightening the lock nut 30 so as to hold the base member 11 and the weight relatively immovable. It is to be noted that the upper wall 5 of the weight 27 is curved coincident to the curvature of the base, so that the upper end of the weight will contact the base throughout its length.

While I have shown and described the 10 preferred embodiment of the present invention, I do not wish to confine myself to the exact details of construction shown, as various forms, modifications and arrangements of the parts as shown may be had 15 without departing from the spirit and scope of the invention as claimed.

What I claim as new is:—

1. A ship's table comprising a top, a bowl-shaped base carried by the top, angularly-disposed dove-tailed grooves formed in the bottom of the base, a bolt having a head seated in said grooves, a weight carried by said bolt, and ball-bearing carrying members for supporting the base.
- 25 2. A ship's table comprising a top, a hollow semi-spherical base member carried thereby and being of increased cross-sectional area at the center thereof, angularly-disposed dove-tailed grooves formed in said member, said grooves terminating in enlarged openings at their outer ends and all meeting in the center to provide a single

opening, a bolt having a head disposed within said grooves, a weight carried by said bolt, means for holding the bolt and weight immovable relative to said base member, supporting legs, and antifriction members between the legs and base.

3. A ship's table comprising a top, a bowl-shaped base carried thereby and being continuously curved, dove-tail grooves formed in said base and having straight bottom walls, a headed bolt slidably mounted in said grooves, a weight carried by said bolt and having its upper face curved coincident to the curvature of the outer face of the base, means for holding the base and weight relatively immovable, and anti-friction supporting members for said base.

4. A ship's table comprising a base member, supporting legs therefor, radially-disposed dove-tailed grooves communicating at their inner ends and terminating in enlarged openings at their outer ends, and a weight supporting member adjustably mounted in said grooves and adapted to be selectively positioned therein.

In testimony whereof I affix my signature in presence of two witnesses.

STANISLAW GRZYBOWSKI.
